UNITED STATES PATENT OFFICE

JOHN O'FALLON CLARK, OF UNIVERSITY CITY, MISSOURI, ASSIGNOR TO AMERICAN MANGANESE STEEL COMPANY, OF CHICAGO, ILLINOIS, A CORPORATION OF MAINE

REPLACEMENT LINK

Application filed April 20, 1931. Serial No. 531,370.

This invention relates to links which, for the purpose of adapting them to be introduced into a chain or otherwise connected with existing open structural elements, are composed of two link members, separable in a cleavage plane, and having each an opening in its side admitting the element to which it is to be connected; and especially to that sub-class of cleavage links in which the plane of separation involves the side members as well as the end members of the link, and the spaced ends which define the opening in each link member are anchored upon the solid side of the complementary link member to resist spreading of the members under tension incident to their use.

The object of the present invention is to provide an improved construction of links of this kind, and particularly a construction in which the anchorage of the ends of the members will secure them more firmly against relative movement, besides being of a design which can be finished by grinding and therefore adapted for successful production from manganese steel or other alloy calling for the use of the grinder in finishing. And to these ends, the invention consists in forming upon the solid or continuous side of each link member a boss or enlargement which fills the opening of the complementary link member when the two members are assembled and, adjacent this filler and at either end thereof, a T-shaped recess or seat in the cleavage plane of the link, with the head of the T extending entirely across the link member at the end of the filler, transversely to the direction of tension when the link is in service, while the stem of the T is longitudinal to the direction of tension, and forming upon the ends which define the opening in each member, T-shaped anchors adapted to enter the said recesses and, by engagement with shoulders that define the recesses, interlock firmly against relative movement in the cleavage plane either transversely to or in the direction of the line of tension imposed upon the link when in use. Such a form of interlock can be finished by grinding in a manner to insure firm seating; and the two link members, when constructed as described, are adapted to be held in assem-

bly with each other by ordinary rivets passing through them and intersecting their plane of cleavage, some of the rivets being closely associated with the T-shaped anchoring connections so as to prevent the T-shaped anchors from drawing out of the T-shaped recesses.

In the accompanying drawings—

Figures 1 and 2 represent, respectively, the inner and outer faces of a link member, or two identical link members constructed in accordance with the present invention and adapted for assembly in a cleavage plane which includes both sides and both ends of the link.

Figure 3 is an end view of the member shown in Figure 1, and also constitutes an end view of the member shown in Figure 2 if inverted.

Figure 4 is a side view of either of the members shown in Figures 1, 2 and 3, looking toward the side of the link member in which the opening is made, and which, in the preferred form of the invention, is of materially less thickness than the continuous side of the link member.

Figure 5 is a section on the line 5x—5x of Figure 1; and

Figure 6 is a perspective view showing two similarly designed complementary link members assembled to form a complete link.

The two complementary link members A and B are preferably identical in design and, as shown more clearly in Figures 3, 4 and 6, these members separate upon a plane of cleavage C which, while including both sides and both ends of the link, is at such a substantial angle to the general plane of the link that it leaves the solid or continuous side 1 of the link with the major thickness of the link member and the side containing the opening 2 with a minor thickness.

Openings 2 of the members A, B, are defined by T-shaped anchors 3, the heads 4 of which extend transversely of the direction of tension imposed upon the link when in use, while reduced shanks or necks 5 of said anchors extend approximately in the direction of such tension. The continuous sides 1 of the link members are formed with lugs or bosses 6 designed to enter and fill the space

between the heads 4 of the anchors 3 and at either end of said boss 6 said sides are formed with transverse recesses 4a that receive the heads 4, and intersecting said transverse recesses are longitudinal recesses 5a that receive the shanks 5. This method of anchorage leaves on either side of the shank 5, and as 10 arresting shoulders for the heads 4, embracing lugs 7, 8 which hold the anchors 3 firmly against movement in the cleavage plane both longitudinally of and transversely to the tension which the link encounters in use so long as the link members are held against separation; and this, with the present construction 15 of link, may be conveniently realized by introducing ordinary rivets through the openings 9, each of which is sufficiently near one of the anchors 3 to prevent it from being drawn out of the recess in which it is seated.

20 An important advantage of the particular form of anchorage herein shown and described is that it admits of dressing the work-piece by the grinder, which in turn renders it practicable to produce the link from manganese steel or other alloy which cannot be 25 economically machined. Moreover, a link constructed as herein described is very rigid in use, under the load imposed, and the resistance to deflection is identical in both link 30 members since the dimensions of the two members are alike at the point where the adjacent links come into bearing when the link is under tension, namely, in the plane including the major axis of the link and perpendicular to the plane of the link.

I claim:

1. A chain link, comprising two complementary link members separated in a cleavage plane that includes both the end and side portions of the link; each link member having at one side a receiving opening for an element to which the link is to be connected, and on its other side a filler for the opening of its complementary link member; said link members being constructed with means for anchoring the ends of the complementary link adjacent its said filler; said anchoring means comprising two T-shaped recesses on each link member lying substantially in the plane of cleavage, with the head of each recess extending transversely across an end of the filler and the necks of the recesses extending longitudinally of the link, and two anchors constituting confines of the side opening of the member and formed with T-heads entering the transverse portions of the recesses and with shanks entering the necks thereof; and the confines of the T-shaped recesses comprising shoulder lugs against which said anchors abut longitudinally and laterally under forces tending to displace the anchors.
2. A link as described in claim 1, in which the faces of the ends of the link members through which they meet the faces ad-

acent to the fillers are plane and unobstructed, and the link members have rivet holes extending through them in directions intersecting the cleavage plane and in positions which bring a rivet in close proximity to the shank 70 of each T-shaped anchor.

Signed at St. Louis, Missouri, this 8th day of April, 1931.

JOHN O'FALLON CLARK.
